J. Cox,
Oscillating Mortiser.
N° 99,064. Patented Jan. 25, 1870.

Inventor;
John Cox.

United States Patent Office.

JOHN COX, OF PORTLAND, OREGON.

Letters Patent No. 99,064, dated January 25, 1870.

IMPROVEMENT IN MORTISING-MACHINE.

The Schedule referred to in these Letters Patent and making part of the same.

To all whom it may concern:

Be it known that I, JOHN COX, of Portland, in the county of Multnomah, and State of Oregon, have invented a new and improved Mortising-Machine; and I do hereby declare that the following is a full, clear, and exact description of the construction and operation of the same, reference being had to the accompanying drawings, making a part of this specification, in which—

Figure 1 is a view in perspective.

Figure 2 is a front elevation.

Figures 3 and 4 are detached views of several parts. This invention consists of two metallic standards, set each on a pair of curved legs, and at a sufficient distance from each other to admit of placing between them a metallic frame, in the form of the arc of a circle, which frame has sockets on its sides large enough to enclose the said standards, and has a longitudinal slot of sufficient width to receive a lever that passes between them, and is pivoted, at its lower end, between legs projecting downward from the sides of the curved frame, and has, at its extreme lower end, a set of teeth, which gear with a toothed comb rising from the upper side of the cutter, so that when the lever is moved to and fro upon its pivot, the cutter may receive an oscillating movement sufficient to cause it to enter the wood to be mortised.

In the drawings—

F are two metallic standards, set each upon two curved legs, the said standards being at a sufficient distance from each other to admit of the introduction between them of a bent frame, K, which frame may be raised or lowered on the standards F, by reason of a system of cog-wheels, D E, upon the frame, each of which has a smaller pinion on its shaft, one of which pinions gears with a set of teeth made in one edge of one of the standards F. By rotating, by means of a crank, the cog-wheels, the curved frame K may be raised or lowered at pleasure, their rotation, when not moved by the crank, being prevented by a pawl, y.

The frame K has a slot running lengthwise of it, sufficiently wide to receive a lever, A, the lower end of which is pivoted between the lower ends of legs a, extending down, one from each of the sides of the frame K.

On the lower end of the lever A is a toothed comb, G, which gears with a similar toothed comb, G', on the upper side of the cutter-head H, the latter being pivoted between the legs a a.

By swinging the lever A to and fro, it will be seen that the cutter-head H is oscillated. This oscillation causes it to cut into or mortise the piece of wood placed beneath it.

In order to firmly secure the piece of timber V, I pass a chain, P, about it, and pass the ends of said chain over hooks in the ends of a forked lever, M, whose forks are on the outside of the standards F, and are pivoted at their ends to the extremities of a shaft, N, passing loosely through one of the adjacent pairs of curved legs, and longer than the combined width of said legs, so that it has some play in them, from end to end.

By turning the lever M down, when the chain is on the hooks, the chain is made to firmly clamp the stick of timber, and may be held in any required position, by means of a toothed bar, L, pivoted to the curved legs.

The oscillations of the lever A impart a reciprocating movement to a bar, B, pivoted to the lower part of the lever, and resting upon one end of the bent frame K.

The bar B carries a pawl, C, that engages with the teeth of the wheel D, and causes the latter, in conjunction with the other cog-wheels of the system, and the rack in F, to feed the frame K, with the cutter-head, down to its work.

The pawl C is controlled by a set-screw, S, which, by raising or lowering its rear end, causes it to take up one or more of the teeth of the wheel D, as may be required to feed the same faster or slower.

Having thus described my invention,

What I claim as new, and desire to secure by Letters Patent, is—

1. The frame K, carrying the cutter-head H, and provided with the system of cog-wheels D E, &c., combined with the standards F, one or both of which have teeth, in the manner set forth, for the purpose of raising and lowering the cutter-head.

2. In combination with the above, the lever A, provided with the toothed comb G, the cutter-head H, provided with the toothed comb G', the bar B, and pawl C, all arranged and operating substantially as described.

JOHN COX
